Attorneys.

UNITED STATES PATENT OFFICE.

WILLIAM H. ROSE, OF JERSEY CITY, NEW JERSEY.

CONTAINER.

Application filed July 18, 1922. Serial No. 575,798.

To all whom it may concern:

Be it known that I, WILLIAM H. ROSE, a citizen of the United States, and resident of Jersey City, Hudson County, State of New Jersey, have invented certain new and useful Improvements in Containers, of which the following is a specification.

This invention relates to containers and particularly to a container having heavy walls of paper or other fibrous material and metallic closures for the ends of the same.

The objects of the invention are to provide a container having a heavy inner wall formed by a tube of heavy fibrous material and a heavy outer wall formed by wrapping paper material around the inner wall; to provide means for securely fastening the heads or closures to the container; and generally to provide a container which is strong and durable and which can be constructed in large sizes for use in the packing and transportation of material.

The invention is set forth in detail in the following specification and illustrated in the accompanying drawings in which:

Figure 1 is a longitudinal sectional view of a container involving the invention and illustrating one arrangement for securing the heads to the container;

Figures 2, 3, 4, 5, 6 and 7 are fragmentary sectional views illustrating various means or combination of means for use in securing the heads to the body of the container; and

Figure 8 is a side view of a portion of a head or closure illustrating one of the forms of fastening means employed.

The body of the container forming the subject matter of the present invention is made up of two portions, an inner cylindrical wall 10 and an outer cylindrical wall 11. These walls as illustrated in the drawing are made quite heavy so as to be strong and durable and capable of withstanding severe usage. In constructing the container a cylindrical tube having a heavy wall is employed for forming the inner wall 10 of the container. The outer wall 11 is formed by wrapping paper material around the inner wall 10 until the outer wall 11 attains the thickness desired and such thickness may of course be varied depending upon the strength of container desired. In wrapping the paper material to form the outer wall 11 it is of course to be under-

stood that glue is applied to the paper so that when wrapped around the inner wall 10 the layers of paper will adhere and form the outer wall 11.

The heads or closures 12 for the ends of the container are secured in position between the inner and outer walls 10 and 11. This is accomplished by providing each head 12 with a flange 13 which lies between the walls forming the body of the container and which surrounds and closely fits the inner wall. It will be understood that the heads 12 are applied to the tube forming the inner wall 10 before the paper material forming the outer wall 11 is wrapped around the inner wall, so that such material is also wrapped around the flanges 13 of the heads. The heads 12 may be provided with any desired form of opening 12a to which a suitable cover may be applied.

Various means may be employed for securing the heads or closures 12 to the container constructed as above described. In the form of construction shown in Figure 1 the flanges 13 are provided with outwardly extending radial projections 14 which projections are made of sufficient length to perforate one or more of the layers of paper material as it is wrapped about the inner wall 10 in the process of forming the outer wall 11. These projections thus serve to securely fasten the heads 12 in position.

In the form of construction illustrated in Figure 2 the flange 13 of the head is provided with a series of inwardly inclined prongs 15 which extend toward the inner end or base of the flange 13. It will be apparent that such inclined projections will engage and embed themselves in the outer surface of the inner wall of the container when the head is forced into position on the tube forming the inner wall of the container.

A further arrangement for securing the heads 12 in position is illustrated in Figure 3 in which the flange 13 is provided with a series of openings 16. This arrangement is also shown in detail in Figure 8. With a construction of this kind it will be understood that when the layers of paper forming the outer wall 11 are wrapped around the inner wall 10 the glue will extend through the openings 16 and will thus securely lock the flange 13 to the material forming the inner and outer walls of the container.

Figure 4 illustrates a combination of se-

curing means, the flange 13 in this construction being provided with outwardly projecting radial prongs 17 like the prongs 14 of Figure 1 and also with inwardly inclined 5 prongs 18 like those illustrated in Figure 2. This arrangement provides means by which the flange is firmly secured to both the inner and outer walls of the container.

In Figure 5 there is also illustrated a combination of fastening means, the flange 13 of this arrangement having outwardly projecting radial prongs 19 together with openings 20 like that illustrated in Figure 8. This construction also provides a plurality 15 of means for securing the flange in position.

In the form of construction illustrated in Figure 6 the flange 13 is provided with inwardly inclined prongs 21 like those illustrated in Figure 2 and also with a series of 20 openings 22 similar to those illustrated in Figure 8.

Figure 7 illustrates an arrangement in which all three forms of fastening means heretofore referred to are employed. In this 25 arrangement the flange 13 is provided with outwardly projecting radial prongs 23, inwardly projecting inclined prongs 24 and openings 25 so that when this form of flange is employed a very secure means is provided 30 for attaching the head to the body of the container.

It will be observed that the heads 12 in each form of the device illustrated is provided with an outwardly extending annular 35 flange 26 which lies beyond the outer periphery of the inner wall 10 of the container. It will be understood that this flange 26 is made of sufficient width to overlie the ends of the outer wall 11 so that this flange 40 constitutes means by which the ends of the built up wall is protected. The width of the flange 26 may of course be varied depending upon the thickness of the outer wall 11.

In wrapping the paper material to form the outer wall 11, it may be found desirable in some cases to use thin paper for the inner layers, so that the outwardly projecting prongs on the flanges 13 may easily penetrate the same and to use heavier paper material for the outer layers.

It will be apparent that the foregoing provides a construction in which the walls of the container may be made strong and durable and of practically any thickness desired so that the construction of very large containers with heavy walls is rendered possible. It also provides means by which the heads are permanently and securely locked 50 in position on the container and which serve to completely protect the ends of the container.

Having thus described my invention what

I claim as new and desire to secure by Letters Patent is:

1. The method of forming a container having a heavy inner wall and a heavy outer wall and simultaneously securing a closure to the same which consists in wrapping a plurality of layers of paper material around a heavy tube of paper material and over a flange on the closure extending around and closely fitting the outer surface of said tube.

2. The method of forming a container 75 having a heavy inner wall and a heavy outer wall and simultaneously securing a closure to the same which consists in wrapping a plurality of layers of paper material around a heavy tube of paper material and over a 80 flange on the closure extending around and closely fitting the outer surface of said tube, said flange being provided with a plurality of outwardly extending prongs which engage one or more of the layers of paper material wrapped around said flange.

3. The method of forming a container having a heavy inner wall and a heavy outer wall and simultaneously securing a closure to the same which consists in wrapping a 90 plurality of layers of paper material around a heavy tube of paper material and over a flange on the closure extending around and closely fitting the outer surface of said tube, said flange being provided with a plurality 95 of openings for receiving glue as the paper is wrapped over said flange.

4. The method of forming a container having a heavy inner wall and a heavy outer wall and simultaneously securing a closure 100 to the same which consists in wrapping a plurality of layers of paper material around a heavy tube of paper material and over a flange on the closure extending around and closely fitting the outer surface of said tube, 105 said flange being provided with inwardly extending prongs for engaging the outer surface of the inner tube.

5. The method of forming a container having a heavy inner wall and a heavy outer wall and simultaneously securing a closure to the same which consists in wrapping a 110 plurality of layers of paper material around a heavy tube of paper material and over a flange on the closure extending around and closely fitting the outer surface of said tube, 115 said flange being provided with a plurality of outwardly extending prongs which engage the paper material wrapped around said flange and said flange also being provided with a plurality of openings for receiving glue as the paper is wrapped over said flange.

In testimony whereof I hereunto affix my signature.

WILLIAM H. ROSE.
